OPHTHALMIC MOUNTING

Chester G. Salmon, Greece, N. Y., assignor to
 Bausch & Lomb Optical Company, Rochester,
 N. Y., a corporation of New York

Application May 28, 1935, Serial No. 23,882

3 Claims. (Cl. 88—47)

The present invention relates to ophthalmic mountings and more particularly to means for attaching rimless mountings to lenses.

One of the objects of this invention is to provide an ophthalmic mounting having improved means for attaching it to a lens. Another object is to provide an ophthalmic mounting having independent lens engaging straps. A further object is to provide an ophthalmic mounting in which the lens engaging straps can be adjusted to retain lenses of different thicknesses. A further object is to provide an ophthalmic mounting which can be readily assembled and taken apart without the use of screws. These and other objects and advantages reside in certain novel features of construction, arrangement and combination of parts as will hereinafter be more fully set forth and pointed out in the appended claims.

Referring to the drawing:

Fig. 1 is an enlarged fragmentary front view of a lens connection embodying my invention.

Fig. 2 is a rear view of same.

Fig. 3 is a horizontal section of same.

One embodiment of this invention is illustrated in the drawing wherein 10 indicates a bridge which is secured to a lens 11 by straps 12 and 13. The bridge 10 and shoe 14 are fixed to the strap 12 which has an aperture 15 opposite an opening 16 in the lens 11. The strap 12 also has a hole 17 beyond the edge of the lens 11 and a groove 18 in the inner surface of the strap 12 extends between the aperture 15 and hole 17.

The front strap 13 is preferably imperforate and has an anchoring means opposite the opening 35 16, which comprises a cavity 19 with a restricted neck 20. Beyond the edge of the lens 11, the strap 13 has a tongue 21 which extends through the hole 17 in the strap 12. A groove 22 in the inner surface of the strap 13 extends from the 40 anchoring means longitudinally along the strap 13 and tongue 21 and a notch or depression 23 is formed in the tongue and opens into the groove 22.

In assembling this mounting the lens 11 is placed between the straps 12 and 13 and the tongue 21 is placed in the hole 17. With the members held in this position a fusible material 24 such as the pyroxylin material sold under the trade name of "Lumarith" or a low melting point 50 metallic alloy, is introduced through the aperture 15 and heat is applied. The fusible material 24 extends through the aperture 15 and opening 16 into the anchoring means in the strap 13 and also extends along the grooves 18 and 22. After 55 the fusible material 24 has hardened, the end of the tongue 21 extending through the hole 17 beyond the surface of the strap 12, is cut off. As the straps 12 and 13 are independent, lenses of any thickness can be mounted and the fusible 60 material 24 extending along the grooves 18 and

22 completely fills the space between the straps 12 and 13 and the lens 11 so that the lens is tightly held even though the straps 12 and 13 do not rest exactly upon its surfaces.

From the foregoing it will be apparent that I am able to attain the objects of my invention and provide an ophthalmic mounting having a connection in which the straps are independent and can engage lenses of different thickness and form a tight and permanent union therewith. Various 10 modifications can, of course, be made without departing from the spirit of my invention or the scope of the appended claims.

I claim:

1. An ophthalmic mounting comprising two independent spaced straps positioned, respectively, on opposite sides of a lens having an opening, one of said straps having an aperture opposite said opening, the other of said straps having anchoring means opposite said opening, one of said straps having a hole therethrough, a tongue on the other strap extending through said hole, a groove in the inner face of the strap having the tongue, said groove being in communication with said opening and extending along said strap and tongue, and a fusible retaining element positioned in said opening and said aperture, engaging said anchoring means and filling said groove.

2. An ophthalmic mounting comprising two independent spaced straps positioned, respectively, on opposite sides of a lens having an opening, one of said straps having an aperture opposite said opening, the other strap having an anchoring means opposite said opening, one of said straps having a hole therethrough beyond the edge of said lens, the other of said straps having a tongue extending through said hole, a groove in the inner face of the tongue extending along the strap and in communication with said opening, a groove in the inner face of the other strap also connecting the first groove and the opening, and a fusible element extending through said aperture and said opening, engaging said anchoring means and filling said grooves.

3. An ophthalmic mounting comprising two independent spaced straps positioned, respectively, on opposite sides of a lens having an opening, one of said straps having an aperture opposite said opening, a hole beyond the edge of the lens, and a groove in its inner surface connecting said aperture and said hole, the other of said straps having anchoring means opposite said opening, a tongue adapted to extend through said groove and a groove in its inner surface beginning at said anchoring means and extending longitudinally of 55 said tongue and a fusible retaining member extending through said aperture and said opening, engaging said anchoring means and substantially filling said grooves.

July 21, 1936.
